CLAIM

I claim the ornamental design for a conduit hanger adapter, as shown and described.

DESCRIPTION

FIG. 1 is an isometric view showing my new design; FIG. 2 is a top view thereof; FIG. 3 is a bottom view thereof; FIG. 4 is a first end view thereof, wherein a second end view is identical to FIG. 4; FIG. 5 is a first end view thereof; and, FIG. 6 is a second end view thereof. The invention pertains to an ornamental design for a conduit hanger adapter. The solid lines represent the bounds of the claimed design, whereas those features shown in broken lines form no part of the claimed design.
